UNITED STATES PATENT OFFICE.

CHESTER E. HENNING, OF BRADNER, OHIO.

GAS-ENGINE STARTER.

1,318,446.

Specification of Letters Patent. Patented Oct. 14, 1919.

Application filed February 24, 1919. Serial No. 278,626.

To all whom it may concern:

Be it known that I, CHESTER E. HENNING, a citizen of the United States, and a resident of Bradner, in the county of Wood and State 5 of Ohio, have invented a certain new and useful Gas-Engine Starter; and I do hereby declare the following to be a full, clear, and exact description of the invention, such as will enable others skilled in the art to which 10 it appertains to make and use the same, reference being had to the accompanying drawings, and to the characters of reference marked thereon, which form a part of this specification.

15 This invention relates to starting devices for internal combustion engines and particularly to devices of this kind of the priming type.

The object of my invention is to provide 20 a simple and efficient device for use in connection with an engine cylinder to facilitate the introduction of a priming charge therein and the lighting of such charge or of a charge of gas drawn into the cylinder by 25 suction action of the engine in the usual manner, and its primary object is to improve on the starting device described and claimed in my former United States Letters Patent 1,080,689, dated December 9th, 1913.

30 The invention is fully described in the following specification, and while, in its broader aspect it is capable of embodiment in numerous forms, a preferred embodiment thereof is illustrated in the accompanying drawings 35 in which,—

Figure 1, is a top plan view of a device embodying the invention, partly open and screwed into an engine cylinder which is fragmentarily shown. Fig. 2 is a side elevation thereof with the device in closed and locked position. Fig. 3 is an outer end elevation thereof, and Fig. 4 is a side elevation of the valve and its locking means with parts broken away.

45 Referring to the drawings, 1 is the body of a device embodying the invention, it being of plug form with its inner end threaded as at 2 to adapt it to be screwed into an opening in an engine cylinder 3. The body 1 50 is provided with a longitudinal bore or passage 4 extending from its inner end to near its outer end and provided preferably at its top side with a laterally projecting opening 5, which is disposed at the outer side of the 55 cylinder in which the body is secured. The

inner end of the body 1 is provided with a conical valve seat in which a valve 6 is adapted to seat to close the communication between said passage and the interior of the cylinder. The valve 6 opens inwardly relative to the cylinder and has a stem 7 projecting from its inner side through the passage 4 and through a bearing passage 8 provided in the outer end portion of the body. The outer end portion of the stem 7 projects beyond the outer end of the body 1 and pivotally carries a lock finger 9, which is intended to coact with the outer cam end of the extension 10 on the outer end of the body 1 to draw and hold the valve in closed position.

For the purpose of adjustment, the finger 9 has its inner end forked to provide spaced bearing parts 11, which are pivotally mounted on the stem and it is held against longitudinal movement on the stem 75 by a nut 12 threaded thereon. This nut is locked in adjusted position by making the outer end of the stem in two sections, which are threaded in opposite directions into the nut and coöperate to have binding engagement therewith. The outer end section of the stem is designated 13 and is provided with a head 14 at its outer end.

In the use of my device, a charge of gasoline or other suitable priming fluid may be 85 introduced into the cylinder through the passage 4—5 of the device.

In starting an engine by the use of my device the valve 6 is moved to open position by releasing the locking finger 9 from its 90 engagement with the cam surface of the extension 10 and it is allowed to rest on one or the other of the top shoulders of said extension. A charge of gasoline or other suitable priming fluid is then introduced into 95 the engine through the opening 4—5 of the device, being drawn therein by suction action upon a turning of the engine crank, and a lighted match or other igniting agent is then held to the opening 5 to ignite the 100 charge. If gas is being used as an operating fluid, a charge may be drawn into the engine by turning the crank and such charge then ignited by holding a lighted match to the opening 5. Upon the compression stroke 105 of the piston the valve 6 will be closed but it will be opened again on the suction stroke, providing the lock finger 9 rests on the longer one of the two shoulders on the extension 10. If the finger rests on the shorter 110

one of such shoulders it will automatically drop into locking engagement with the cam end of such extension upon a closing of the valve, as is apparent. Should wear occur between the valve and its seat or between the finger and its coacting locking surface, such wear may be compensated for by an adjustment of the finger on the stem.

I wish it understood that my invention is not limited to any specific construction, arrangement or form of the parts as it is capable of numerous modifications and changes without departing from the spirit of the claim.

Having thus described my invention, what I claim as new and desire to secure by Letters Patent is,—

A device of the class described comprising a body member of plug form adapted to be screwed at its inner end into an engine cylinder casing opening and having a passage extending outwardly therethrough from its

inner end and open at its outer end without the cylinder, said member having an extension at its outer end projecting longitudinally thereof and forming a cam surface and shoulders at the ends of said cam surface, a valve for closing the inner end of said passage and seating under internal cylinder pressure, a stem projecting from said valve outwardly through said member and beyond the outer end thereof, and an element carried by the outer end of said stem for swinging movements transverse thereto and adapted when in one position to coact with said cam surface to hold the valve in closed position and when in another position to rest on one of said shoulders to permit opening and closing movements of the valve and stem.

In testimony whereof I have hereunto signed my name to this specification.

CHESTER E. HENNING.
